(57) **CLAIM**

The ornamental design for an air tank, as shown and described.

DESCRIPTION

FIG. 1 is a top plan view of an air tank.

FIG. 2 is a bottom plan view of the air tank of FIG. 1.

FIG. 3 is a first end elevation view of the air tank of FIG. 1.

FIG. 4 is a second end elevation view of the air tank of FIG. 1.

FIG. 5 is a first side elevation view of the air tank of FIG. 1.

FIG. 6 is a second side elevation view of the air tank of FIG. 1.

FIG. 7 is an isometric view of the air tank of FIG. 1.

FIG. 8 is another isometric view of the air tank of FIG. 1; and,

FIG. 9 is a perspective view of an air tank shown in use on a motorcycle.

The broken and dash-dot-dash boundary lines shown illustrate portions of the air tank and environment that form no part of the claimed design.

1 Claim, 9 Drawing Sheets
